No. 723,780.

PATENTED MAR. 24, 1903.

W. MITCHELL.

RESERVOIR FOR VAPOR BURNERS.

APPLICATION FILED APR. 6, 1901. RENEWED NOV. 18, 1902.

NO MODEL

UNITED STATES PATENT OFFICE.

WILLIS MITCHELL, OF MALDEN, MASSACHUSETTS, ASSIGNOR TO THE MITCHELL GAS GENERATOR AND BURNER COMPANY, OF BOSTON, MASSACHUSETTS, A CORPORATION OF NEW JERSEY.

RESERVOIR FOR VAPOR-BURNERS.

SPECIFICATION forming part of Letters Patent No. 723,780, dated March 24, 1903.

Original application filed October 3, 1900, Serial No. 31,810. Divided and this application filed April 6, 1901. Renewed November 13, 1902. Serial No. 131,264. (No model.)

To all whom it may concern:

Be it known that I, WILLIS MITCHELL, a citizen of the United States, residing at Malden, in the county of Middlesex and State of Massachusetts, have invented certain new and useful Improvements in Reservoirs for Vapor-Burning Heaters; and I do hereby declare the following to be a full, clear, and exact description of the invention, such as will enable others skilled in the art to which it appertains to make and use the same.

This invention relates to reservoirs for vapor-burning heaters especially adapted to be mounted on and moved with a smoothing-iron, although available for use with other implements, utensils, and structures, movable and immovable; and it consists in the construction and combination of parts hereinafter set forth and claimed.

20 In the accompanying drawings, Figure 1 represents a central section of a reservoir embodying my invention and the handle and supports whereby it is attached to a smoothing-iron. (Not shown.) Fig. 2 represents a 25 plan view of the reservoir and coupling-block without the superposed parts; and Fig. 3 represents a detail plan view, taken from below, of the air-receptacle and the block which supports the same.

30 A designates a smoothing-iron handle, having recesses a in its upper ends to receive the upper ends of a U-shaped handle-support B, the lower part of which is broken away, the said ends being fastened by screws a' to the 35 said handle. A bifurcated reservoir-support O is similarly fastened at its lower ends by screws a^2 to the said handle-support and is provided with a screw-threaded upwardly-presented centrally-bored neck O', on which 40 is screwed a centrally-bored metallic coupling-block P'. The bore of said neck is ex- 45 tended obliquely down through one of the arms of the reservoir-support and out at its side to receive a gasolene-pipe H for supply-

ing the smoothing-iron burner, (not shown,) making a continuous passage from the said pipe to a socket p, formed in the top of the said coupling-block and filled with filtering

material p' . The said coupling-block constitutes the base and means of attachment of 50 the gasolene-reservoir P. The bifurcated standard O is bent out laterally, as shown in Fig. 1, to avoid the handle A and afford room for grasping the same. The top of said reservoir is provided with a concavity O², having 55 a central opening. On the edge of said opening rests an annular external flange q on the upper part of a tubular internally-screw-threaded coupling-block Q, extending down into the said reservoir. The top of this 60 coupling-block is provided with an annular groove q', Fig. 2, having a raised concentric annular ridge q² in its middle. The bore of this block receives a corresponding screw-threaded tubular stem V' of the base-block 65 V, which supports a vertical air-pump cylinder S and a globular air-receptacle u exterior and concentric thereto. These parts S and u are rigid with the said block, their lower ends fitting tightly on an annular shoulder or flange V² thereof. The base-block V is provided with an oblique passage v above 70 said shoulder or flange V², which passage connects the interior of air-receptacle u. The said block V has also a tapering central 75 downward outlet s, through which air is forced to the interior of the reservoir F by the piston S², operated in said cylinder by its piston-rod S', having a knob or handle S⁴ screwed on its upper end. The said cylinder 80 is closed at its slightly-enlarged upper end t' by a cap S³, which is centrally perforated for the passage of the said piston-rod and provided with an internally-screw-threaded wall or annular flange t, that engages the similarly-threaded upper end t' aforesaid. The 85 said piston is provided with the usual packing S⁵.

The bore of tubular stem V', constituting an extension of outlet s, is enlarged below the 90 latter to receive a valve R for closing the same, and a helical spring R', surrounding the stem r of said valve and holding the latter up against its seat. The said valve-rod works through a central hole r² in a detachable block or nut r', this hole being large 95

enough to allow the passage of air down around the said stem, although additional holes z , Fig. 3, in nut or block r may be used, if preferred.

5 The bottom of the base-block V has an annular ridge x , which rests on the ridge q^2 of block O' when the blocks O and V are screwed together. A ring W of fibrous packing is fitted into groove q , and the ridges x and q^2 bite into said packing-ring from above and below, making a tight joint. The concavity o^2 allows the air-receptacle u to be set lower than would otherwise be possible, thus increasing the compactness and strength of my 15 device. The said concavity leaves also an annular space around it at the upper end of the reservoir, since the liquid fuel will not rise higher than the central opening through which it is supplied. This space receives air 20 and the vapor or gas of said liquid fuel.

Each downward motion of the pump-piston in starting the operation of the device drives air received through the inlet y down through outlet s , the bore of stem V' , and the hole r^2 25 into the reservoir, also through oblique passage r into air-receptacle u , where it is compressed. When the piston moves upward, the valve R closes the outlet s , but leaves open the passage v , through which and said 30 bore and holes the compressed air within said receptacle u exerts pressure on the liquid in reservoir P . This pressure is increased by the reciprocating movement of the piston, but will continue feeding the liquid fuel for some 35 time after such movement has ceased and until the pressure of vapor or gas in the said reservoir is sufficient to that end.

Having thus described my invention, what I claim as new, and desire to secure by Letters 40 Patent, is—

1. A reservoir for liquid fuel having a tubular coupling-block fitted into its top and extended down within it, in combination with an air-pump and air-receptacle, supported on 45 the said reservoir, and a base-block for said

pump and receptacle provided with a tubular stem which screws down into the said coupling-block substantially as set forth.

2. A reservoir for liquid fuel having a tubular coupling-block fitted into its top, in 50 combination with an air-pump and an air-receptacle supported on the said reservoir, and a base-block for said pump and receptacle, having a stem which screws into said coupling-block, the said coupling-block being provided on its top with an annular groove having an annular ridge in its middle and the said base-block having on its bottom a corresponding ridge, in order that these ridges 55 may be forced into interposed packing and 60 make a tight joint when the blocks are screwed together substantially as set forth.

3. In combination with a reservoir for liquid fuel having in its top a concavity with a central opening, a tubular block fitted into 65 said opening and an air-pump having a base attachment engaging with said block for mounting it thereon, an air-receptacle surrounding the said pump, supported by the same base and set into the same concavity 70 and means for conducting liquid from said reservoir substantially as set forth.

4. An air-pump and surrounding air-receptacle, in combination with a base-block common thereto, having a bore and separate passages from said bore to said receptacle and the pump-cylinder, a spring-pressed valve and a liquid-reservoir communicating with the said bore, the said valve being arranged to leave open the passage between the liquid-reservoir and the air-receptacle, while preventing the escape of air or gas from either of them to the pump-cylinder substantially as set forth.

In testimony whereof I affix my signature 85 in presence of two witnesses.

WILLIS MITCHELL.
